INSULATED FOOD JAR

Robert Lincoln Waddington, London, England, assignor
to Insulex Limited, a corporation of Great Britain

Filed Sept. 9, 1965, Ser. No. 86,914

Claims priority, application Great Britain Mar. 30, 1965

Term of patent 3½ years

(Cl. D58—17)

FIG.1

FIG.2

FIG.3

FIGURE 1 is a front perspective view of an insulated food jar showing my new design;

FIGURE 2 is a rear perspective view; and

FIGURE 3 is a top plan view thereof.

The container wall is smooth except for the vertical ribs extending longitudinally under each handle-receiving block.

I claim:

The ornamental design for an insulated food jar, substantially as shown and described.
